[57] CLAIM

The ornamental design for a welding stinger attached visor, as shown and described.

DESCRIPTION

FIG. 1 is a frontal perspective view of a welding stinger attached visor showing a preferred form of my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view, the opposite left side being a mirror image thereof; and,

FIG. 7 is an enlarged fragmentary sectional view taken along line 7—7 in FIG. 2.
